UNITED STATES PATENT OFFICE.

PERCY J. CREASEY, OF CABIN CREEK, WEST VIRGINIA.

INJECTOR.

1,383,985.

Specification of Letters Patent. Patented July 5, 1921.

Application filed June 7, 1920. Serial No. 387,103.

To all whom it may concern:

Be it known that I, PERCY J. CREASEY, a citizen of the United States of America, residing at Cabin Creek, in the county of Kanawha and State of West Virginia, have invented new and useful Improvements in Injectors, of which the following is a specification.

The object of the invention is to provide a simple and efficient construction of injector for use as a boiler feeding mechanism and more especially to provide a double tube injector having self-priming or automatically priming features to the end that whether used as a lifting or non-lifting injector, it may be primed by the admission of the steam without supplemental manipulation or re-adjustment; and furthermore to provide an injector mechanism which may be converted into and used as an apparatus of the single tube type; and with these objects in view, the invention consists in a construction and combination of parts, of which a preferred embodiment is shown in the accompanying drawing, wherein:

Figure 1, is a sectional view showing the parts arranged for use as a double tube injector.

Fig. 2, is a similar view showing the parts, re-adjusted for use as a single tube injector.

Fig. 3, is an enlarged sectional view of the double valve and related parts, the members thereof being shown in full lines in the priming position and in dotted lines in the operative or injector position.

The apparatus embodies a cylindrical casting 10 with which communicates a steam supply pipe 11, the injection of steam to the casing being controlled by the valve 12 arranged to engage the transverse seat 13 and having connected therewith a stem 14 for actuation by the hand lever 15 or the equivalent thereof extending through a suitable stuffing box 16.

In communication with the steam valve seat is a chamber 17 which in turn is in communication with the chamber 18 by means of an injector nozzle 19 removably fitted as by means of threads 20 in a partition wall 21, and respectively in connection with the chambers 17 and 18 are the pressure tube 22 and the suction tube 23. The pressure tube and suction tube are provided with detachable sections 22^a and 23^a connected with the body portions respectively by couplings 24

and 25, said section 22^a being extended into the section 23^a and provided with a terminal suction nozzle 26 arranged to discharge axially into a suction thimble 27 which is removably seated in the tube section 23^a and is adapted to be dismounted when the coupling member 25 is removed to permit of the use of the suction tube 23 without cooperation with the pressure tube 22 as a single tube injector.

Fitted upon a seat 28 in the injector nozzle 19 is an injector valve 29 of which the stem 30 extending through the chamber 17 carries a piston head or disk 31 mounted in a cylindrical cavity 32 formed in the pressure valve 12 under such conditions as to permit of a limited un-seating movement of the pressure valve as indicated in Fig. 3 without unseating the injector valve 29. The pressure valve at the outer end of the cylindrical cavity 32 is provided with a shoulder 33 for contact with the piston head or disk 31, so that further movement of the pressure valve in a direction from its seat will cause the unseating of the injector valve 29 as shown in dotted lines in Fig. 3.

Separated from the chamber 18 of the casting by a partition 34 is a chamber 35 into which extends a combining tube 36 carried by the said partition and arranged in axial alignment with the injector nozzle 19 so that steam impelled through the nozzle will pass through said combining tube causing a suction in the chamber 18 while disposed in axial alignment with the combining tube is a supplemental nozzle 37 of which the inlet end is in communication with the chamber 35 so that steam passing through the combining tube into the supplemental nozzle will produce a suction in the chamber 35.

In communication with the suction chambers 18 and 35 respectively are the overflow ports 38 and 39 fitted with check valves 40 and 41 arranged in communication when said valves are unseated with the overflow outlets 42 and 43. In the construction illustrated, said check valves are gravity seated and obviously are adapted to be drawn firmly into their seated positions by suction which may be created respectively in the chambers 18 and 35. The auxiliary or supplemental nozzle 37 discharges into the injector outlet 44 which is adapted to be arranged in communication with the boiler pipe feed.

In the operation of the mechanism, the first step is to operate the lever 15 in a direction to the left as viewed in Fig. 1 to unseat the pressure valve 12 until checked by the contact of the shoulder 33 with the piston head or disk 31 and thus to permit the passage of steam from the supply pipe 11 through the valve seat 13 to the chamber 17 and into the pressure tube 22. The steam 5 thence passes through suction nozzle 26 to the suction nipple or thimble 27 to produce a suction in the chamber represented by the enlargement 45 of the suction pipe section 23^a and thus induces an upward flow of 10 water through the suction pipe 46. The steam passing upward through the suction tube 23 and into the chambers 18 and 35 causes the unseating of the check valves 40 and 41 controlling the overflow ports where 15 it finds an outlet, and when the water carried forward by the suction and injector action of the steam through the nozzle 26 reaches the outlet 43 and the chambers 18 and 35 have been primed, the operating 20 lever should be drawn forward to the limit of its movement in the same direction as previously, to cause the unseating of the injector valve 29 whereupon the steam will pass directly from the chamber 17 through 25 the injector nozzle 19 and into the combining tube to cause a suction in the chamber 18 which will immediately seat the valve 40. Also the steam passing through the combining tube and into the auxiliary nozzle 30 37 will produce a suction in the chamber 35 which will seat the priming valve 41 and the injector will then operate effectively to carry the water forward and through the discharge outlet 44.

40 The injector valve 29 is made of a diameter adapting it to pass through the opening bounded by the shoulder 33 of the pressure valve and the latter is provided with a removable cap screw 47 so that after the 45 injector valve has been inserted through the pressure valve and the piston head or disk 31 arranged in the cylindrical cavity 32, the cap screw may be fitted in place to connect the pressure valve and injector valve under 50 such conditions as to permit of lost motion of the injector valve to provide for the successive unseating of said pressure and injector valves as hereinbefore described in connection with the full operation of the injector mechanism.

Also as will be obvious from the foregoing description the disconnection of the couplings 24 and 25 will permit of the use of the suction tube independently of the pressure tube for injector purposes when a single tube construction is preferred without involving the necessity of a separate structure and from the manufacturer's standpoint without involving the additional patterns or 65 castings.

The invention having been described, what is claimed as new and useful is:—

1. An injector having a pressure chamber and a suction chamber, an injector nozzle connecting the said chambers, pressure and suction tubes respectively in communication with said chambers, the pressure tube being provided with a suction nozzle discharging axially into the suction tube, an overflow port in communication with the suction chamber and having an inwardly seating valve, a pressure valve for controlling the communication of steam to the pressure chamber, and an injector valve seated in the injector nozzle to connect with the pressure valve for actuation thereby, the former being capable of unseating movement independently of the latter.

2. An injector having pressure and suction tubes of which the former is provided with a suction nozzle discharging axially into the latter, an injector nozzle, a pressure valve for admitting steam to the pressure tube and the injector nozzle and provided with a cylindrical cavity, and an injector valve seated in the injector nozzle and having its stem provided with a piston head or disk mounted in said cavity of the pressure valve for movement independently thereof.

3. An injector having pressure and suction tubes of which the former is provided with a suction nozzle discharging axially into the latter, an injector nozzle, a pressure valve for admitting steam to the pressure tube and the injector nozzle and provided with a cylindrical cavity, and an injector valve seated in the injector nozzle and having its stem provided with a piston head or disk mounted in said cavity of the pressure valve for movement independently thereof, the pressure valve having a shoulder for engagement with said piston head or disk for imparting unseating movement to the injector valve.

4. An injector having pressure and suction tubes of which the former is provided with a suction nozzle discharging axially into the latter, an injector nozzle, a pressure valve for admitting steam to the pressure tube and the injector nozzle and provided with a cylindrical cavity, and an injector valve seated in the injector nozzle and having its stem provided with a piston head or disk mounted in said cavity of the pressure valve for movement independently thereof the pressure valve having a shoulder for engagement with said piston head or disk for imparting unseating movement to the injector valve, and the injector valve being of a diameter less than that of the said shoulder.

5. An injector having a double valve consisting of a steam pressure member and an injector member, said pressure member being provided with a cylindrical cavity fitted

with a removable cap screw and provided with a contracted forward end forming a stop shoulder, and the latter having its stem provided with a piston head or disk fitted in said cavity the diameter of the injector member being less than that of the contracted portion of the pressure member.

6. An injector having a compression chamber and a suction chamber, an injector nozzle connecting the said chambers, pressure and suction tubes respectively in communication with said chambers, the pressure tube being provided with a suction nozzle discharging axially into the suction tube, an overflow port in communication with the suction chamber and provided with an inwardly seating valve, a pressure valve controlling the admission of steam to the pressure chamber, an injector valve controlling communication between the pressure chamber and the suction chamber, and a common operating means for both the pressure and injector valves, the pressure valve being unseatable by said means independently of the injector valve.

7. An injector having a pressure chamber and a plurality of suction chambers, an in-

jector nozzle connecting the pressure chamber with one of said suction chambers, a combining tube connecting said first-named suction chamber with the other suction chamber, valved overflow ports in communication respectively with said suction chambers, a pressure valve controlling the admission of steam to the pressure chamber, an injector valve controlling the passage through the injector nozzle, and parallel pressure and suction tubes respectively in communication with said pressure chamber and the first-named suction chamber, the pressure tube being in communication with the suction tube and provided with a suction nozzle arranged to direct a jet axially into the pressure tube, a suction thimble removably seated in the suction tube in axial alinement with said suction nozzle, and couplings detachably securing the pressure and suction tubes to the injector proper whereby the pressure tube and its associated elements may be removed to convert the injector into the single tube type.

In testimony whereof I affix my signature.

PERCY J. CREASEY.
